UNITED STATES PATENT OFFICE.

CHARLES L. GOODRUM, OF BROOKLYN, NEW YORK, ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

1,221,169.

Specification of Letters Patent. Patented Apr. 3, 1917.

Application filed September 11, 1916. Serial No. 119,511.

To all whom it may concern:

Be it known that I, CHARLES L. GOODRUM, a citizen of the United States, residing at Brooklyn, in the county of Kings and State 5 of New York, have invented certain new and useful Improvements in Machine-Switching Telephone-Exchange Systems, of which the following is a full, clear, concise, and exact description.

10 This invention relates to telephone exchange systems involving private branch exchange working.

In the circuit arrangement of this invention some of the subscribers in the private 15 branch exchange may be called by any other subscriber in the system by means of automatic switches. Others of the private branch exchange subscribers, however, can receive calls through the intervention of an 20 operator at the private branch exchange; that is to say, when a connector is set upon any of such lines, instead of the station thereof being automatically signaled, the private exchange operator is signaled and, 25 by means of her listening key, bridges her talking set across the calling line, and inquires the wants of the calling party. Means is provided whereby she may then either allow the line upon which the connector has been set by the outside party to 30 be signaled, or release the connector, informing the calling party that the call cannot be completed.

The circuit arrangement of this invention 35 is particularly useful in such systems wherein automatic working is desired for the majority of the private branch exchange subscribers, and it is not desirable that certain of such subscribers be directly accessible to 40 outside parties for various reasons, among which may be mentioned the waste of time incident to people calling officers in the company served by the private branch exchange, and asking questions which could be more 45 readily taken care of by employees. In the circuit arrangement of this invention such calls are diverted by the operator to the proper channels.

Referring to the accompanying drawing, 50 which illustrates only so much of a telephone exchange system as is necessary for a comprehension of the invention, the invention will be best understood by describing, by reference to such drawing, the detailed operation of the system.

The removal of the receiver at substation A, causes a line finder, of which only the brushes *b*, *b'* and terminals *t*, *t'* are shown, to be automatically set in motion in any well-known manner, to hunt for the calling line. When the finder connects with such line, the first selector FS, the brushes 2, 3 and 4 and terminals 5, 6 and 7 only of which are shown, is set by the sender S at the calling substation in the well-known manner 60 upon a trunk terminating in a connector C at the private branch exchange. It will be understood that although only one selector FS is shown, the connection would in practice be built up over a chain of such switches. 65

When the calling line has been thus extended to the connector C, the stepping relay 8 thereof is energized over the calling line circuit, and by attracting its armature, energizes a slow relay 9. This relay, in attracting its right armature, interposes a break in the circuit of release magnet Rel, and at its front contact connects the back contact of stepping relay 8 to the primary magnet PM of the connector. 70

The calling party now operates his sender S to transmit the tens digit of the wanted number. The sender, in restoring, interrupts the line circuit a number of times corresponding to the tens digit of the wanted 85 number. Upon each retraction of the stepping relay armature 8, an impulse is sent over the following circuit to primary magnet PM to position a set of brushes 10, 11, 12 and 13 in operative relation to the group of 90 terminals containing those of the wanted line: free pole of battery, magnet PM, side switch arm 14 and its first contact, armature 50 and back contact of busy relay BR, conductors 15 and 46, right armature and front 95 contact of relay 9, armature and back contact of relay 8 to ground. A slow relay 16, in parallel with magnet PM, energizes upon the first impulse and, being slow-acting, remains energized during the transmission of the 100 impulses. When the sender S restores and maintains the line circuit closed, relay 8 remains energized. After an interval the slow relay 16 becomes deenergized, opening the circuit of the connector side switch escape 105 magnet 17, closed when this relay was energized. The escape magnet 17, in deenergizing, releases the side switch into position 2. In this position the secondary magnet SM is substituted for the primary magnet PM. 110

110

The calling party now operates his sender S to transmit the units digit of the wanted number. The secondary magnet SM, in response to these impulses, steps the positioned 5 set of brushes 10, 11, 12 and 13 over the terminals of the selected group. The slow relay 16 is again energized in parallel with the secondary magnet SM, and again energizes the escape magnet 17. When the 10 sender S restores and maintains the line circuit closed, the slow relay 16, after an interval, deenergizes, opening the circuit of escape magnet 17, which passes the side switch to position 3.

15 Assuming that the terminal 43 of the line upon which the connector has been set is a non-restricted line and is idle, the following circuit is closed for the escape magnet 17 to close the ringing circuit: escape magnet 17, arm 22 and its third contact, armature and back contact of ringing cut-off relay RCO, conductors 23, 24 to ground at the left armature and front contact of relay 9. Magnet 17, in attracting its armature, closes the ringing circuit as follows: ground, ringing generator 25, battery, relay RCO, left armature and back contact of relay 21, armature and front contact of magnet 17, arm 26 on its third contact, 25 brush 12, terminal 27, through the bell 28 and condenser 29 at the substation B, terminal 30, brush 11, arm 31, and its third contact to ground.

When the party at substation B removes 35 his receiver, the relay RCO energizes, opening the circuit of escape magnet 17, which thereupon deenergizes and passes the side switch to position 4. In moving out of position 3 the ringing circuit is opened, and in 40 position 4 talking current is fed to the called party over the following circuit: free pole of battery, retardation coil winding 33, conductor 34, arm 31 and its fourth contact, brush 11, terminal 30, through the telephonic 45 apparatus at substation B, terminal 27, brush 12, arm 26 and its fourth contact, conductor 35, retardation coil winding 36 to ground. Talking current is fed to the calling party over the windings of relay 8.

50 The calling and called ends of the talking circuit are conductively separated and inductively united by condensers 37 and 38.

Assuming now that the connector was set on terminals 41, 42, 43, 40 of a restricted 55 idle line, whose terminal 41 is grounded, the lamp 19 becomes lighted over the following circuit: grounded terminal 41, bush 10, key OK, lamp 19, right-hand armature and back contact of relay BR, arm 20, and its 60 second contact, relay 21, free pole of battery. The brush 10 engages the terminal 41 before the slow relay 16 has time to deenergize and open the circuit of escape magnet 17. The side switch is thus held in position 2 65 until after relay 21 has had time to energize.

Relay 21, in attracting its right armature, closes a locking circuit for itself independently of arm 20, and in attracting its left armature, interposes a break in the ringing circuit before the escape magnet has had time to attract its armature and close the same in position 3. The operator, noticing the lighted lamp 19, actuates her listening key LK, which bridges her talking set (not shown) across the calling line. After talking with the calling subscriber, she may by depressing the key OK, permit the line upon which the connector rests to be signaled, or, by pressing the release key RK, release the connector. In the former case 75 the depression of the key OK unlocks relay 21, and extinguishes the lamp 19. The relay 21, in retracting its left armature, connects the ringing generator 25 to the called line, from which point on the operations are 80 85 the same as already traced.

On the other hand, assuming the connection is not to be extended, the operator so informs the calling party and depresses the release key RK, which results in the energization of the release magnet Rel over the 90 following circuit: free pole of battery, magnet Rel, primary off-normal contact PON, conductors 39 and 40' key RK, to ground. When the connector reaches its normal position 95 the off-normal contact PON opens and unlocks the release magnet.

Assume now that the line upon which the connector is set is busy. The test terminal 40, in such event, is grounded over the side 100 switch arm 41' and the third contact of the connector connected with such line or a side switch arm at the finder, depending on whether the line is a called or calling line. Going back to that point in the operation 105 where the calling party transmits the units digit of the called number, it will be remembered that the slow relay 16 is energized in parallel with the secondary magnet SM, and that this relay at its armature and front 110 contact completes a circuit for the escape magnet 17, the side switch being at this time in position 2. When the connector brushes 10, 11, 12 and 13 reach the selected set of terminals 41, 42, 43 and 40, and before the relay 16 has had time to retract its 115 armature, the following circuit is closed in position 2 of the side switch over grounded terminal 40, of the busy line, brush 13, arm 41' and its second contact, right winding of relay BR, and free pole of battery. Relay 120 BR in attracting its inner armature locks itself up over side switch arm 45 and its second contact. At armature 51 it closes a circuit to maintain the escape magnet 17 energized to hold the side switch in position 2, at armature 50 it interposes a break in the circuit of magnet SM to prevent the calling subscriber from transmitting any more impulses, and at its outer left armature con- 125 130

nects a source of busy tone current 42' to the conductor 35 and thence to the calling line to inform the calling party that the desired line is busy.

5 When such party replaces his receiver the connector release magnet *Rel* is energized over the following circuit: free pole of battery, magnet *Rel*, contact PON, armature and back contacts of relays 9 and 8, to ground. Magnet *Rel*, restores the connector and when the brush shaft thereof reaches its normal position, it opens contact PON and unlocks the release magnet. This magnet in operating restores the side switch in the well-known manner. The right armature of relay BR is provided in order to prevent unnecessarily signaling the operator in the event the selected line is a restricted line and busy.

20 What is claimed is:

1. In a telephone exchange system, the combination with restricted and non-restricted telephone lines, an automatic switch wherein said lines terminate, a sender adapted to set said switch on said lines, a source of signaling current, an operator's position, a telephone set and supervisory signal thereat, means for automatically connecting said source to non-restricted lines when the switch is set thereon, automatic means actuated when said switch is set on restricted lines to prevent the connection of said source thereto and to operate said signal, manual means controlled by the operator for connecting her set in circuit with the calling line, and means controlled by the operator for connecting said source to the line.

2. In a telephone exchange system, the combination with restricted and non-restricted subscribers' telephone lines, an automatic switch wherein said lines terminate, senders associated with said lines adapted to set said switch thereon, a source of signaling current, an operator's position, a telephone set and supervisory signal thereat, means for automatically connecting said source to non-restricted lines when the switch is set thereon, automatic means actuated when said switch is set on restricted lines to prevent the connection of said source thereto and to operate said signal, means controlled by the operator for connecting her set in circuit with the calling line, and means controlled by the operator for connecting said source to the line or for releasing the switch.

3. In a telephone exchange system, the combination with restricted and non-re-

stricted subscribers' telephone lines, an automatic switch wherein said lines terminate, a side switch therefor, senders associated with said lines adapted to set said switch thereon, a source of signaling current, an operator's position, a telephone set and supervisory signal thereat, means actuated when said switch is set on an idle line for advancing said side switch to the next position to connect said source of signaling current to such line, a circuit closed in said position to include said source in circuit with the called line if such line is a non-restricted line, a relay actuated when said switch is set on a restricted line for interposing a break in said ringing circuit, a key controlled by the operator for connecting her set to the calling line, and a key for de-energizing said relay to close the ringing circuit.

4. In a telephone exchange system, the combination with restricted and non-restricted telephone lines, an automatic switch wherein said lines terminate, senders associated with said lines adapted to set said switch thereon, a source of signaling current, an operator's position, a telephone set and supervisory signal thereat, means for automatically connecting said source to idle non-restricted lines when the switch is set thereon, means actuated when said switch is set on restricted lines to prevent the connection of said source thereto and to operate said signal, means controlled by the operator for connecting her set in circuit with the calling line, means controlled by the operator for connecting said source to the line, a busy back signaling apparatus at said switch, and a relay operated if the non-restricted line is busy to prevent the operation of such signal and to connect said busy-back apparatus to the calling line.

5. In a telephone exchange system, the combination with restricted and non-restricted telephone lines, of an automatic switch wherein said lines terminate, operator's equipment and a source of signaling current, means for automatically connecting said source to non-restricted lines when the switch is set thereon, automatic means actuated when said switch is set on restricted lines to prevent the connection of said source thereto, and means controlled by the operator for connecting said source to the line.

In witness whereof, I hereunto subscribe my name this 8th day of September A. D., 1916.

CHARLES L. GOODRUM.
